UNITED STATES PATENT OFFICE

GERTRUDE SCHOENFELD, OF ASTORIA, NEW YORK

DESIGN FOR A BOTTLE

Application filed April 8, 1932. Serial No. 43,424. Term of patent 14 years.

To all whom it may concern:

Be it known that I, GERTRUDE SCHOENFELD, a citizen of the United States, residing at Astoria, Long Island, Queens County, State of New York, whose post-office address is 2595 Forty-third Street, Astoria, Long Island, Queens County, State of New York, have invented a new, original, and ornamental Design for a Bottle, of which the following is a specification, reference being had to the accompanying drawing, forming part thereof.

Fig. 1 is a side elevation;

Fig. 2 is a similar view at right angles to Fig. 1; and

Fig. 3 is a top plan view of Fig. 2; of a bottle showing my new design.

I claim:

The ornamental design for a bottle substantially as shown.

GERTRUDE SCHOENFELD.
